UNITED STATES PATENT OFFICE.

WILLIAM N. SMITH, OF YONKERS, NEW YORK.

SUPPORT FOR INSULATORS.

No. 878,679.

Specification of Letters Patent.

Patented Feb. 11, 1908.

Application filed April 28, 1906. Serial No. 314,130.

To all whom it may concern:

Be it known that I, WILLIAM N. SMITH, a citizen of the United States, residing at Yonkers, in the county of Westchester and State 5 of New York, have invented certain new and useful Improvements in Supports for Insulators, of which the following is a specification, reference being had to the drawing accompanying and forming part of the same.

10 My invention relates to devices for supporting the insulators which carry an electrical conductor, and pertains more particularly to supporting devices in the nature of pins, mounted on cross arms or similar fixtures 15 carried by poles or equivalent structures. Heretofore the most common practice has been to fix the pins in holes in the cross arm. A wooden arm is seriously weakened by such holes and is liable to crack or split, as in fact 20 not infrequently happens when there is any considerable strain on the pins. Making the holes smaller in diameter causes less impairment to the strength of the arm, but the reduced diameter of the pin at that point 25 weakens the pin, so that it is itself liable to breakage. Furthermore, the arm deteriorates more rapidly from exposure to the elements, since the holes afford access for moisture into the interior of the wood, causing the 30 same to decay prematurely. In any case, shrinkage of the wood is liable to loosen the pin, however firmly it may have been set originally, and tightening the pin is at best not an easy matter.

35 My present invention is designed to overcome these defects, by providing a pin or support which can be affixed to the arm without in any way impairing the strength of the latter.

40 A further object is to provide fastening means which can readily be tightened whenever from any cause the pin may have become loosened.

A further object is to provide a support in 45 which the material composing the same is distributed to the best advantage, that is to say, to provide a support of maximum strength for a given weight.

Still another object is to provide a support 50 of this character which can be manufactured at comparatively small cost.

In carrying out my invention in its preferred form I employ a pin having an enlargement constituting a base which rests on 55 the cross arm and which is preferably large enough to extend entirely or substantially

across the arm. Immediately above the base is a transverse aperture through which passes a U-shaped bolt, embracing the arm. On the projecting ends of the bolt is a cross 60 plate or strap held by nuts, by means of which the whole may be firmly bound, thus securing the pin rigidly on the arm. For the purpose of strengthening the pin it may be provided with reinforcing webs extending 65 from it to the base, and in order to obviate any possibility of the pin slipping on the arm the underside of the base may be provided with a suitable number of pointed projections or teeth, which, under the pressure of 70 the binding bolt, bite into the wood of the arm, or, in the case of a metal arm, extend into suitable openings formed therein.

The embodiment thus briefly described is 75 illustrated in the annexed drawing, in which

Figure 1 is a sectional view showing the insulator pin in place on a cross arm. Fig. 2 is a top plan view of the same. Fig. 3 is a side elevation of the same.

The insulator pin proper is indicated by A, 80 and B is the flaring base thereof. As shown, the base is preferably hollowed on its underside to reduce the weight of the device. In plan the base is substantially rectangular, with incurving side edges b. Extending 85 from the angles b' are strengthening webs b², which reinforce the pin against strains exerted longitudinally of the cross arm, and extending from the centers of the side edges are webs b³, which reinforce the pin against 90 strains exerted transversely of the arm.

Extending through the axis of the pin, and immediately above the base, is a transverse aperture D, to receive the U-bolt E, which straddles or embraces the arm and has its 95 threaded ends e, e', extending below the arm, through apertures in the ends of a strap or cross plate F. On the ends of the bolt are nuts e², e³, by means of which the bolt may be drawn down, thus binding the pin on the 100 arm as tightly as desired. For additional security the underside of the base of the pin is preferably provided with downwardly projecting teeth or points b⁴, which bite into the arm, or in the case of a metal arm, extend into suitable apertures therein; and thus effectively prevent the base from slipping on the arm.

As will be seen in the drawing, the transverse opening D is preferably made flaring at 110 its ends, giving the opening something of an hour-glass or hyperboloid shape, with its

smallest diameter at its center, and the flare of the ends of the aperture is preferably greatest along the vertical diameter, thus making the orifices more or less elliptical in form. An opening of this character, that is, with flaring orifices, permits the U-bolt to be passed through it at any time, either before or after the insulator is secured to the pin, and either before or after the pin is placed in position on the cross arm. The upper end of the pin, which receives the insulator, may be of any form or contour, depending on the type of insulator which it is to support. It might even be formed with an eye, to receive an insulating bushing, but as the formation of this part of the pin is wholly immaterial it is unnecessary to illustrate the same further than as shown in the drawing.

The pin and its base and strengthening webs are all integral with each other, and the device is therefore much stronger than if the pin and base were made in separate pieces and merely fastened together. The arched contour of seat for the bolt in the aperture is best adapted to transmit the downward pressure of the U-bolt and permits the use of a bolt with a curved or rounded top instead of one at right angles to the legs, which latter form would be less easily threaded through the opening, while the use of the radial reinforcing webs from the base to the pin gives substantially the strength and rigidity of a cone without the same amount of metal. In other words, the given weight of metal is distributed so as to give the maximum strength. Including the binding nuts the entire support consists of but five pieces. The pin and base may be formed by casting, stamping, or forging, and the bolt may be readily bent from a bar of the proper length, while the holes in the strap to receive the ends of the bolt may be punched. Hence the only machining required is the threading of the bolt ends. The rod forming the U-bolt may be of any standard size and hence can be obtained readily and cheaply in any market. The pointed projections or teeth on the base prevent any slipping or sidewise displacement of the pin if the same should become loose by shrinkage of the arm, while such shrinkage may at any time be taken up and the pin firmly tightened merely by screwing up the butts. If desired, the insulators can be cemented or otherwise fastened to the pins in the shop or stock room, and the U-bolt can be passed through the opening therefor after the device is placed in position on the arm. In this way the cementing of the insulator and pin can be done under the best

conditions, in the shop or stock room, and a firm connection insured, which might not be the case if the assembling were all done in the field, where the weather often constitutes a serious obstacle to good work. At the same time, the danger of breakage is largely avoided. The size and relative proportions of the various parts may be varied indefinitely, to provide the constructions best adapted for circuits of different voltages, for different sizes of cross arms, etc.

I am aware that it has been proposed before to secure an insulator pin to a cross arm by means of a more or less U-shaped bolt straddling the arm, but these prior constructions have all lacked the simplicity and cheapness necessary to bring them into general use.

What I claim is:

1. The combination with a one-piece insulator-support, comprising a pin and a transverse base formed integral with each other, and having a transverse perforation above the base, said base being adapted to seat on a cross arm; of a U-bolt extending through the perforation with its bend seated in the perforation, the bolt being adapted to straddle or embrâce the cross arm; a strap or cross plate having apertures through which the ends of the bolt pass; and nuts on the ends of the bolt, whereby the whole may be firmly bound upon the cross arm; as set forth.

2. As a new article of manufacture, a one-piece insulator support, consisting of a pin having a transverse perforation near one end thereof, and a transverse base, formed integrally with the pin, on the end of the latter adjacent to the said perforation, as set forth.

3. As a new article of manufacture, a one-piece insulator support, consisting of a pin having an integral transverse base at one end and a transverse perforation above the base, and radially arranged strengthening webs between the pin and the base, as set forth.

4. As a new article of manufacture, a one-piece insulator support, consisting of a pin having a transverse base formed integrally at one end thereof, with integral strengthening webs arranged radially about the pin between the pin and the base, and having a transverse perforation above the base, the ends of the perforation being flaring, and the perforation constituting an arched seat, as set forth.

WILLIAM N. SMITH.
